Primary Examiner — Richard E Chilcot*(74) Attorney, Agent, or Firm* — NSIP Law**(57) CLAIM**

We claim the ornamental design for a display screen or portion thereof with graphical user interface, as shown and described.

DESCRIPTION

The sole FIGURE is a front view of a display screen or portion thereof with graphical user interface, showing our new design.

The broken lines illustrating portions of the display screen or portion thereof with graphical user interface form no part of the claimed design.
